UNITED STATES PATENT OFFICE.

CLIFFORD J. ALPAUGH, OF TRENTON, NEW JERSEY.

FUSE-PLUG.

1,277,679.

Specification of Letters Patent.

Patented Sept. 3, 1918.

Application filed January 18, 1918. Serial No. 212,430.

To all whom it may concern:

Be it known that I, CLIFFORD J. ALPAUGH, a citizen of the United States of America, residing at Trenton, New Jersey, have invented a new and useful Fuse-Plug, of which the following is a specification.

My present invention relates to fuse plugs and the objects of the invention are to provide a simple practical and inexpensive form 10 of plug which can be easily assembled and tested and in which the fuse will be properly housed and protected to prevent escape of molten metal when the fuse "blows".

Briefly the invention comprises a tubular 15 body member substantially closed at its outer end but open at its inner end to receive a cap member which closes said open end of the tubular body and carries both the circuit terminals and the fusible element connecting 20 the same. The screw shell which forms one of the circuit terminals is utilized as a means for securing the two parts of the body together and is formed with an integral extension introverted into the tubular body member 25 and constituting a conducting strip to which the inner end of the fuse element is connected.

Other features of the invention will appear as the specification proceeds.

30 The accompanying drawing illustrates the invention in a practical and preferred form, wherein:—

Figure 1, is a longitudinal sectional view of the fuse plug.

35 Fig. 2, is a perspective view of the fuse and terminal carrying element as it appears ready for attachment to the tubular body member.

Fig. 3, is a view of the contact end of the 40 plug, parts being broken away and shown in section.

The plug is made up of two main parts, a main body member 5 in the form of a tubular shell having an open inner end and a substantially closed outer end, and a cap member 6 designed to close the open inner end of the first member. These two members are made of suitable insulating material and constitute, when assembled, a closed chamber for the fuse, said chamber usually having 45 ventilating openings for the escape of gases such as those indicated at 6^a provided in the otherwise closed outer end of the main body member.

50 The two insulating members of the plug are secured together by the screw shell con-

tact 7, said shell having an end flange 8 overlying the rim of the cap member 6 so as to confine the same against the end of the tubular body member. The screw shell is preferably secured to the body member by indenting portions 9 thereof over suitable locking shoulders 10 provided on the outer surface of said tubular member. The outer surface of said member is otherwise preferably left 65 plain as indicated at 11 so as to permit the screw shell being engaged endwise thereover.

The cap member is preferably formed with a protruding annular wall 12 extending, when the parts are assembled, into the 70 tubular body member, said wall forming a cup or pocket receiving the fuse wire 13 and designed to catch the molten fuse metal.

The fuse wire is connected at one end with the center contact 14 and at its opposite end 75 with the screw shell, the connection of the latter being made through the agency of a conducting strip 15 formed integral with the end flange 8 and introverted up into the tubular body member, said conducting strip 80 lying, as indicated in Fig. 1, in between the tubular wall of the body member and the inwardly projecting annular wall 12 of the cap member and being bent over the rim of the latter as indicated at 16 to form a seat to 85 which the end of the fuse wire may be secured as by soldering. This bent inner end 16 of the conducting strip also serves to hold the screw shell and cap member together when the fuse wire is being soldered in place 90 and when said parts, as a single unit, as shown in Fig. 2, are being inserted into the tubular body member. The rim of the cap member is notched at 21 for the passage of the introverted conducting strip. 95

The body member and cap member are preferably keyed non-rotatably together as by providing a lug 17 on the body member taking into a groove 18 in the annular wall of the cap member. Also the screw shell is 100 preferably keyed non-rotatably to the cap member as by making the cap member with a central angular projection 19 projecting through a correspondingly angularly shaped opening 20 in the lower end of the screw shell.

The plug is assembled by simply inserting the cap member in the screw shell, soldering or otherwise securing the inner end of the fuse to the terminal portion 16 of the screw 110 shell conducting strip and then applying this fuse and terminal carrying unit to the

tubular body member, the annular portion of the cap member sliding up into the tubular body and the screw shell sliding up over the tubular body, where it is secured by indenting over the locking shoulders. The construction of the fuse and terminal carrying parts as a single unit enables these parts in their finally connected form being tested before being applied to the body member of the fuse. The test can thus be made while the fuse and all parts of the terminals are fully exposed.

I claim:

1. A fuse plug comprising, a tubular member of insulating material closed at its outer end and open at its inner end, a cap piece of insulating material closing the open inner end of the tubular body member, means for keying said two members together to prevent relative rotation between the same, a screw shell having an end flange engaging over the cap member, said body member having a substantially smooth external surface whereby the screw shell may be slipped endwise over the same to hold the cap member thereto, said body member further having an external shoulder and the screw shell having a portion indented over said shoulder to thereby secure the body member, cap member and screw shell together, the screw shell having a conducting strip integral with the end flange thereof introverted into the tubular body member, an end contact on the cap member and a fusible link connected between the conducting strip and end contact.
2. A fuse plug comprising, a tubular member of insulating material closed at its outer end and open at its inner end, a cap piece of insulating material closing the open inner end of the tubular body member, means for keying said two members together to prevent relative rotation between the same, a screw shell having an end flange engaging over the cap member, said body member having a substantially smooth external surface whereby the screw shell may be slipped endwise over the same to hold the cap member thereto, said body member further having an external shoulder and the screw shell having a portion indented over said shoulder to thereby secure the body member, cap member and screw shell together, the screw shell having a conducting strip integral with the end flange thereof introverted into the tubular body member, an end contact on the cap member, a fusible link connected between the conducting strip and end contact, the tubular body member and cap member having interengaging elements securing said two members against relative rotation.
3. A fuse plug comprising, a tubular body member of insulating material open at its inner end and substantially closed at its outer end, said body member having a sub-

stantially smooth exterior formed with locking shoulders, a cap member closing the open inner end of the tubular body member and having a tubular wall extending into the tubular body member, one of said members having a lug and the other having a recess receiving the same, whereby the two members are non-rotatably connected together, a screw shell engaged longitudinally over the relatively smooth exterior of the tubular body member, said screw shell having an end flange engaged with the cap member and having portions indented over the locking shoulders, whereby to secure all of said parts together, a conducting strip integrally attached to the end flange of the screw shell and extending up into the tubular body member between the wall of said tubular member and the tubular wall of the cap member, the inner end of said conducting strip being bent over the inner end of said tubular wall, an end contact on the cap member and a fusible link connected at one end with said contact and connected at its opposite end with the bent over inner end of the conducting strip.

4. A fuse plug comprising, a screw shell having an end flange and a conducting strip projecting from said end flange up into the interior of said screw shell, a cap member of insulating material seated in said screw shell and resting on the end flange thereof, said member having a portion projecting beyond the end flange of the screw shell, said projecting portion and screw shell flange having engaging portions preventing relative rotation of the screw shell and cap member, said cap member having a passage in one edge portion thereof for the introverted conducting strip of the screw shell and a projecting annular wall, said conducting strip extending along said annular wall and being bent over the inner end thereof, a center contact carried by the cap member, a fusible link secured between said end contact and the bent over inner end of the conducting strip and a tubular body member adapted to receive said cap member and screw shell.

5. A fuse plug comprising, a screw shell having an end flange and a conducting strip projecting from said end flange up into the interior of said screw shell, a cap member of insulating material seated in said screw shell and resting on the end flange thereof, said member having a portion projecting beyond the end flange of the screw shell, said projecting portion and screw shell flange having engaging portions preventing relative rotation of the screw shell and cap member, said cap member having a passage in one edge portion thereof for the introverted conducting strip of the screw shell and a projecting annular wall, said conducting strip extending along said annular wall and being bent over the inner end thereof, a center con-

tact carried by the cap member, a fusible link secured between said end contact and the bent over inner end of the conducting strip, a tubular body member having a substantially closed outer end and an open inner end adapted to receive the cap member, said body member having a substantially smooth external surface, whereby the screw shell may be engaged longitudinally thereover and locking shoulders adapted to receive indented portions of the screw shell and means for keying the tubular body member and cap member together.

6. In a fuse plug, a tubular body member having a substantially closed outer end and an open inner end and a fuse carrying unit engageable with said tubular body member comprising, a screw shell having an end flange and an introverted conducting strip integral with said end flange, a cap member for closing the open inner end of the tubular body member seated on the end flange of the screw shell and having a tubular wall projecting into the screw shell and into the open inner end of the tubular body member, an end contact carried by the cap member and a

fusible link connected at one end with said end contact and at its other end with the inner end portion of the introverted conducting strip.

7. In a fuse plug, a tubular body member having a substantially closed outer end and an open inner end and a fuse carrying unit engageable with said tubular body member comprising, a screw shell having an end flange and an introverted conducting strip integral with said end flange, a cap member for closing the open inner end of the tubular body member seated on the end flange of the screw shell and having a tubular wall projecting into the screw shell and into the open inner end of the tubular body member, an end contact carried by the cap member; a fusible link connected at one end with said end contact and at its other end with the inner end portion of the introverted conducting strip, engaging parts on the tubular body member and cap member non-rotatably keying the same together and engaging parts on the screw shell and cap member for preventing relative rotation between the same.

CLIFFORD J. ALPAUGH.
